UNITED STATES PATENT OFFICE.

EVERETT A. WENTWORTH, OF ANCON, CANAL ZONE.

ROOFING.

1,258,509.

Specification of Letters Patent. Patented Mar. 5, 1918.

Application filed May 1, 1916. Serial No. 94,750.

To all whom it may concern:

Be it known that I, EVERETT A. WENTWORTH, a citizen of the United States, residing at Ancon, in the Canal Zone, Panama, 5 have invented new and useful Improvements in Roofings, of which the following is a specification.

In laying roofing made up of corrugated shingles, considerable difficulty has been experienced in providing a water-proof joint between the sections, because when the shingles have their adjacent edges overlapped a space is left between certain portions of the shingles due to the thickness of the latter.

15 It is therefore the primary object of this invention to provide a roof covering made up of a plurality of corrugated sections so designed as to permit the same to be quickly and easily laid in a manner to provide an absolute water tight joint between the adjacent shingles, and with a saving of material.

The nature and advantages of the invention will be better understood when the following description is taken in connection with the accompanying drawings, the invention residing in the construction, combination and arrangement of parts as claimed.

In the drawing forming part of this specification like numerals of reference indicate similar parts in the several views and wherein:—

Figure 1 is a plan view showing the manner in which the shingles are arranged.

35 Fig. 2 is a transverse sectional view.

Fig. 3 is a view of one of the sections of the first course.

Fig. 4 is a detail view of the sections of the second course.

40 Fig. 5 is a detail view of one of the bridging sections of the first course.

Fig. 6 is a view in plan of one of the bridging sections of the second and succeeding courses.

45 Referring to the drawing in detail and particularly to Fig. 3, 10 indicates a corrugated shingle which may be manufactured from tile, sheet iron, asbestos or any other suitable material, and may be made of any 50 length and width to suit the builder or manufacturer. The first course of the roof indicated at A is made up of a plurality of these sections, which latter have their lower edges disposed flush with the eave line, and 55 their end edges in contacting engagement,

It is of course understood that the number of sections used in the first course depends wholly upon the area to be covered and the size of the sections.

In Fig. 4 I have illustrated a section 12 of 60 the second course indicated at B and which section is of substantially rectangular outline and has two of its corners cut away as at 11, the angle of the cut being approximately forty-five degrees. It is to be understood 65 that these sections can also be constructed from any suitable material. A plurality of these sections constitute the second course B and are adapted to be arranged end to end with their lower edges overlapping the adjacent edge of the first course A. With the sections thus arranged the cut away portions 11 of the adjacent sections unitedly define a crotch which is wholly disposed above the adjacent edge of the first course A and in 70 alignment with the meeting edges of the respective sections of the course A. As shown the crotch is substantially V-shaped due to the result of cutting the corners away on an angle of approximately forty-five degrees, 75 but it is to be here understood that the outline of the cut away portions can be varied within the scope and spirit of the invention.

In Fig. 5 I have illustrated what is termed a bridging plate 15 adapted to overlie the 80 joint between the meeting edges of the sections 10 of the first course, while one end of this section is formed as at 16 to fit within the cut away portions of the sections of the second course, and as shown in this particular instance is substantially V-shaped as at 85 14. The section 15 is of such length as to bridge the joint between the meeting edges of the sections 10 throughout its entire 90 length. Covering the joint defined by the 95 V-shaped portions 14 when the latter is positioned within the crotch defined by the cut away portions 11 of the section of the second course, is a second bridging section 15' which overlies the said joint and completely covers 100 the same. The third course of the group is made up of a plurality of sections constructed in identically the same manner as the sections 12 of the second course, and by reason of this fact the bridging section 15' has a 105 V-shaped end portion 16' adapted to be fitted within the crotch defined by the cut away portions of the sections of the third course. The opposite end of the section 15 110 can also be made V-shaped to add to the 115

artisticness of the roof construction as a whole, if so desired. This arrangement is continued throughout the number of courses on the roof determined by the surface exposed and the dimensions of the sections of the respective courses, which latter fact also regulates the number of joints between the sections. By reason of the construction and arrangement herein illustrated and described, it will be obvious that I have provided a roofing made up of a plurality of corrugated sections and provided for an absolute water tight joint between the respective sections with the saving of material in consideration of the present day method in laying a roofing of this type.

While it is believed that from the foregoing description the nature and advantages of the invention will be readily apparent, I desire to have it understood that I do not limit myself to the precise construction and arrangement of parts herein illustrated, and that such changes may be resorted to when

desired as fall within the scope of what is claimed.

What is claimed is:—

A roof covering made up of transverse courses with the adjacent edges of the respective courses overlapping, each course comprising a plurality of corrugated sections arranged edge to edge, the sections of the overlapping courses having their corners cut away and unitedly defining substantially V-shaped crotches disposed above the adjacent course, a section bridging the joint between the first sections and having a V-shaped end fitted within said crotching, and an additional section overlapping the joint between the overlapping sections and said crotch and having a V-shaped lower end portion projecting beyond the lower ends of the lower overlapping sections and having a like portion at the other end fitted in the crotch of the sections above.

In testimony whereof I affix my signature. 45
EVERETT A. WENTWORTH.
